VENETIAN BLIND TILT-BAR SUPPORT

Jules Nisenson and Maurice Blazer, New York,
N. Y., assignors to Publix Metal Products Inc.,
New York, N. Y., a corporation of New York

Application June 9, 1945, Serial No. 598,556

5 Claims. (Cl. 160—177)

1

This invention relates generally to the Venetian blind art and more particularly to a tilt-bar support therefor.

In accordance with the majority of Venetian blind constructions, the entire blind is carried by a head-bar which is in turn supported by brackets attached to the window frame or other building opening with which the blind is associated. The slats, in an elevated position thereof, are supported by cords which in turn depend from pulleys usually hidden within the head-bar. When the slats are in the lowered position thereof, they are carried by slat supporting tapes and these in turn are connected at the upper ends thereof to the tilt-bar. It is for this reason that the tilt-bar needs to be relatively strong and this condition is increased in the case of those blinds which are relatively wide, that is to say, longitudinally of the tilt-bar. Where the blind is exceptionally wide, in order to preserve the shape and arrangement of the parts, it would be necessary to unduly increase the thickness of the tilt-bar with a consequently unfavorable effect upon the total appearance of the blind. In order to provide additional support for the tilt-bar at a point or points between the terminals thereof, so-called center supports are provided. Such supports movably position the tilt-bar with respect to the head-bar.

Since in many blind constructions it is desirable that the tilt-bar be removable as a unit from the brackets and the head-bar, it is desirable that such tilt-bar center supports be likewise detachably connectable.

It is, therefore, among the principal objects of the present invention to provide Venetian blind tilt-bar center support construction which is quickly and easily attached to the tilt-bar and to the head-bar.

Another object herein lies in the provision of structure of the class described, which is quickly and easily detachable. Such detachability facilitates the removal of the tilt-bar from the head-bar so that the blind may be cleaned, adjusted or refurbished.

Another object herein lies in the provision of Venetian blind tilt-bar center support construction, which enables the tilt-bar to be rotated axially about the end pins thereof. It is desirable that such rotation may occur without binding or any undue friction so that the Venetian blind may be tilted in the usual manner without excessive effort being required.

Another object herein lies in the provision of a Venetian blind tilt-bar center supporting de-

vice, which is of simple construction, largely wire forms or metal stampings, so that the same may be manufactured in large scale production at low cost and have a consequent wide sale and use.

These objects and other incidental ends and parts and advantages will more fully appear in the progress of this disclosure and be pointed out in the appended claims.

In the drawing in which similar reference characters designate corresponding parts throughout the several views:

Figure 1 is a fragmentary front elevational view showing an embodiment of the invention.

Figure 2 is an enlarged fragmentary vertical sectional view as seen from the plane 2—2 on Figure 1.

Figure 3 is a vertical sectional view taken similarly to Figure 2 but showing the parts in an altered position thereof.

Figure 4 is a fragmentary bottom plan view as seen from the plane 4—4 on Figure 2.

Figure 5 is a fragmentary top plan view as seen from the plane 5—5 on Figure 2.

Figure 6 is an exploded view in perspective.

In accordance with the invention the device generally indicated by reference character 10, is associated with a head-bar 11, and a tilt-bar 12. The head-bar 11 may be of the usual construction having tilt-bar end support brackets 13, only one of which is shown in the drawing. The tilt-bar 12 may be of standard construction and may be provided with end pins 14 (only one of which is shown) which are adapted to be rotatably journaled in the brackets 13. Any desired number of slats 15 (only one of which is shown) may be carried by the tilt-bar 12, by the slat supporting tape 16 (only one shown).

While the device 10 is referred to in the specification and claims as a tilt-bar center support,

it will be understood that the word "center" is used only loosely as it is in the trade, and that the support 10 may be located at any point or points desired between the actual ends corresponding to the end 17 of the tilt-bar 12.

The device 10 includes four separable parts, two of which are assembled to make up the head-bar element 18, and the remaining two of which are assembled to make up the tilt-bar element 19.

The head-bar element 18 includes a relatively stationary track member 20 and a relatively movable hook member 21. The track member is preferably formed by bending to the shape best seen in Figures 2 and 6, a strip of flat stock such as steel. The track member 20 includes an arcuate central portion 22 and has at the ends

thereof the supports 23 and 24. The length of the arcuate portion 22 is preferably substantially greater than the thickness of the tilt-bar 12, but the length thereof is determined by the total rotation which it is desired that the tilt-bar 12 may have about its own longitudinal axis. We have found that the length of the central portion 22 shown permits rotation of the tilt-bar 12 through substantially 180°. The length of the supports 23 and 24 is preferably such that sufficient space remains between the upper surface 25 of the arcuate portion 22 and the under surface 31 to permit the track top engaging portion 26 to freely move along the arcuate track 20. The normally upper ends of the supports 23 and 24 are provided with outwardly extending orificed tabs 27 and 28 which may be penetrated by the screws 29 to secure the track member 20 to the surface 31 of the head-bar 11. Where desired other securing means may be provided to connect the supports 23 and 24 to the head-bar. For example, the supports 23 and 24 may be provided with pointed ends, with or without additional serrations, and may be directly driven into the head-bar in the manner of a large staple.

The movable hook member 21 may be suitably bent to the shape shown in the drawing from wire stock. The upper portion of the hook member 21 includes the track top engaging portion 26 previously referred to, track side engaging portions 32 and 33, the track bottom engaging portions 34 and 35, the vertically arranged connecting portion 36 and the hook portion 37. The hook portion 37 preferably has the terminal 38 thereof arranged generally in an upward direction so that the generally D-shaped ring 39 may be engaged with the hook portion by movement in a substantially downward or angularly downward direction.

The tilt-bar element generally indicated by reference character 19 includes the D-shaped ring 39 and the mounting plate 40. The D-shaped ring 39 includes a rectilinear axle portion 41 joined at the ends thereof to the ends of the arcuate portion 42. The D ring 39 may be of one piece or may have a pair of juxtaposed terminals located preferably in the center of the axle portion 41.

The mounting plate 40 includes a central bearing portion 43 which is preferably rounded and has a relatively internal channel 44 the size of which is substantially equal to or slightly greater than the cross sectional size of the axle portion 41 of the ring 39. Extending outwardly from the bearing portion 43 are the mounting flanges 45 and 46. These flanges may be provided with orifices 47 through which the screws 48 may secure the mounting plate 40 to the upper surface 49 of the tilt-bar 12. The distance between the front and rear edges 50 and 51 respectively of the mounting plate 40 is substantially less than the distance between the points 52 and 53, said points engaging the ends of the axle portion 41 and the arcuate portion 42. This size of the mounting plate 40 with respect to the length of the axle portion 41 permits the ring 39 to shift longitudinally of said axle portion and by virtue of the fact that the channel 44 is of sufficient size the ring 39 may not only move longitudinally of the axle portion 41, but may move pivotally about said axle portion.

As is well known in the art to which the present invention relates various tilt-bar thicknesses are used and also various distances between the tilt-bar and the head-bar are used. The sizes

and arrangement of the parts are such, however, that when assembled as shown the arcuate portion 42 of the ring 39 and the arcuate portion 22 of the ring track member 20, are arcuate with respect to the central longitudinal axis of rotation of the tilt-bar 12, passing through the pins 14. Also, the front and rear surfaces 54 and 55 respectively have a radius of curvature at least equal to the radius of curvature from the central longitudinal axis of the tilt-bar 12. As shown in the drawing the front and rear surfaces 54 and 55 may be even more acutely curved depending upon the aesthetic effect desired. The lower surface of the arcuate portion 22 is disposed at a distance from the central longitudinal axis of rotation of the tilt-bar 12 at least equal to but preferably slightly greater than the distance between said axis and the front surface 54 or the rear surface 55 at their greatest distances from said center, or axis.

Assembly of the parts with each other and with the Venetian blind components is a rapid and convenient matter. At some predetermined location on the head-bar 11 and at a corresponding location on the tilt-bar 12 the head-bar element 18 and the tilt bar element 19 are attached to their respective Venetian blind components. Before the screws 29 are inserted the normally upper portion of the hook member 21 is slipped upon the arcuate portion 22 of the track member 20. Similarly before the screws 48 are inserted the axle portion 41 of the D ring 39 is placed within the channel 44.

When the tilt-bar 12 is placed within the brackets 13 the D ring 39 may be rotated sufficiently so that it may be engaged with the hook portion 37 of the hook member 21, the relatively loose mounting of the hook member 21 on the track member 20 facilitating this operation.

It may be noted at this point that the installation of the mounting plate 40 on the upper surface 49 provides a connection with the tilt-bar without any routing of the tilt-bar being required.

As assembled and with the tilt-bar and the slats in horizontal positions, the parts may take the position as indicated in Figure 2. Upon actuation of the tilting mechanism (not shown) in a direction to cause the forward surface 54 of the tilt-bar 12 to move arcuately downwardly about the longitudinal axis of the tilt-bar 12, the arcuate portion 42 may be moved in a clockwise direction as viewed in Figure 2 until the point 52, that is the juncture of the axle portion 41 of the arcuate portion 42 engages the hook portion 37 at which time the hook member 21 becomes shifted to the right as viewed in Figure 2. Continued rotation of the tilt-bar in the direction last described (clockwise as viewed in Figure 2) will result in the parts taking the position indicated in Figure 3, wherein it will be noted that the D ring 39 has shifted rearwardly or upwardly as viewed in Figure 3, so that the front edge 50 engages the juncture point 53 at the forward end of the D ring 39.

When it is desired to rotate the tilt-bar 12 in the opposite direction, that is, counter clockwise as viewed in Figure 3, the tilt-bar is supported through the medium of the hook 21 by the curved portion of the ring 39 until the position shown by the dot dash lines in Figure 3 is reached wherein it will be noted that the ring 39 has shifted longitudinally with respect to the axle portion 41. In this position the point of

juncture 52 is in engagement with the rear surface 51 of the mounting plate 40.

While there is a tendency for the hook member 21, in reaching a position of equilibrium to tilt so it is radially disposed with respect to the longitudinal axis of the tilt-bar the vertically downward pull of the tilt-bar and the parts suspended therefrom tend to maintain the hook member 21 in a substantially vertical position. Thus for example with the parts in a position indicated by the full lines in Figure 3, upon rotation of the tilt-bar in a counter clockwise direction as viewed in Figure 3, the hook 21 will tend to remain in the forward portion of the stationary track member 20. Thus the hook member would tend to remain in the position shown by the dot dash lines on Figure 2 where it will be seen that the resultant of forces will be exerted to move the D ring forwardly or to the right as shown in Figure 2. Continued counter clockwise rotation of the tilt-bar causes complete shifting of the D ring to its forwardmost position and the shifting of the hook member 21 to its rearmost position, whereby these parts take the position shown by the dot dash lines in Figure 3. Under some conditions the hook will shift first, followed by the shifting of the D ring.

It may thus be seen that we have disclosed a novel and useful Venetian blind tilt-bar support which is adapted to detachably and movably interconnect the tilt-bar at any desired position thereof with the relatively stationary head-bar. By virtue of the fact that there are two movable parts, one movably associated with the head-bar and the other movably associated with the tilt-bar, said parts may shift with respect to each other and with respect to the head-bar and tilt-bar so that substantial conditions of equilibrium may obtain as the tilt-bar is rotated through substantially 180°. The parts of our device are simple in construction and light in weight and may be easily assembled without any special skill. Where desired a plurality of my devices may be used on a single long blind and by virtue of the fact that the tilt-bar does not have to be routed as is done in accordance with prior art constructions, a tilt-bar having a vertical thickness as viewed in Figure 2, of substantially one half of the normal, may be utilized with substantially the same strength characteristics.

The articulate nature of the connection between the tilt-bar and the head-bar provided by our device not only provides for proper support, but also enables the parts to be easily disconnected and reconnected when the blind is disassembled for cleaning or painting, or for other purposes.

We wish it to be understood that we do not

desire to be limited to the exact details of construction shown and described, for obvious modifications will occur to a person skilled in the art.

We claim:

5. 1. A Venetian blind tilt-bar support for use with a head-bar comprising: a head-bar element; and a tilt-bar element; said head-bar element including a stationary track member, and a movable hook member on said track member; said tilt-bar element including a mounting plate, and an orificed member movably connected to said mounting plate; whereby when the tilt-bar is rotated with respect to the head-bar, the hook member may move along the track member and along the orificed member, and the orificed member may move with respect to the mounting plate.
- 10 2. A Venetian blind tilt-bar support for use with a head-bar and a tilt-bar, said support comprising: a head-bar element adapted to be secured to said head-bar; a tilt-bar element adapted to be secured to said tilt-bar and having a mounting plate and a movable orificed member connected thereto; and means slidably connected to said orificed member and to said head-bar element.
- 15 3. A Venetian blind tilt-bar support for use with a head-bar and a tilt-bar, said support comprising: a head-bar element adapted to be secured to said head-bar; and a tilt-bar element adapted to be secured to said tilt-bar and including an orificed member movable in at least two directions with respect to said tilt-bar.
- 20 4. A Venetian blind tilt-bar support for use with a head-bar and a tilt-bar, said support comprising: a track member adapted to be secured to said head-bar; a tilt-bar member having a curved portion and an axle portion connected to said curved portion; means to pivotly and slidably mount said axle portion on said tilt-bar; and link means movably connected to said track and to said curved portion.
- 25 5. A Venetian blind tilt-bar support for use with a head-bar and a tilt-bar, said support comprising: a head-bar element including a stationary curved track having a pair of supports at the ends thereof, said supports being adapted to maintain the track in spaced relation with respect to the head-bar, said supports being adapted to be secured to the head-bar; a tilt-bar element including a D shaped ring having a curved portion and an axle portion, and a mounting plate, said mounting plate being adapted to engage said axle portion and to pivotly and slidably mount the same upon a tilt-bar; and link means slidably engaging said track and said curved portion.

JULES NISENSEN.
